US00D961709S

(12) **United States Design Patent** (10) Patent No.: **US D961,709 S**
Parsons et al. (45) Date of Patent: **** Aug. 23, 2022**

(54) **GOLF CLUB HEAD**

(71) Applicant: **PARSONS XTREME GOLF, LLC**,
Scottsdale, AZ (US)

(72) Inventors: **Robert R. Parsons**, Scottsdale, AZ
(US); **Michael R. Nicolette**, Scottsdale,
AZ (US); **Bradley D. Schweigert**, Cave
Creek, AZ (US)

(73) Assignee: **PARSONS XTREME GOLF, LLC**,
Scottsdale, AZ (US)

(**) Term: **15 Years**

(21) Appl. No.: **29/817,155**

(22) Filed: **Nov. 29, 2021**

Related U.S. Application Data

(60) Division of application No. 29/779,581, filed on Apr.
20, 2021, now Pat. No. Des. 940,262, which is a
continuation-in-part of application No. 29/775,632,
filed on Mar. 24, 2021, now Pat. No. Des. 940,261.

(57) **CLAIM**

The ornamental design for a golf club head, as shown and described.

DESCRIPTION

FIG. 1 is a top perspective view of a golf club head;
FIG. 2 is a bottom perspective view of the golf club head of
FIG. 1;
FIG. 3 is a front elevational view of the golf club head of
FIG. 1;
FIG. 4 is a rear elevational view of the golf club head of FIG.
1;
FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1.
The broken lines shown on the drawings form no part of the
claimed design.
